J. J. COOK

PULL CHAIN TERMINAL

Filed June 3, 1927

INVENTOR

J. J. COOK

BY *Munn & Co.*

ATTORNEYS

UNITED STATES PATENT OFFICE.

JOHN J. COOK, OF CHICAGO, ILLINOIS.

FULL-CHAIN TERMINAL.

REISSUED

Application filed June 3, 1927. Serial No. 196,357.

My invention relates to improvements in terminals for pull chains of electric lights, and it consists in the combinations, constructions, and arrangements herein described and 5 claimed.

An object of my invention is to provide a pull chain terminal which may be made at a minimum cost of light material such as thin sheet brass, but which is so made that it is 10 strong enough to resist a compression strain or a tension strain.

A further object is to provide a terminal which necessitates the use of relatively little material, thereby further decreasing the cost 15 of manufacture.

A further object is to provide a terminal having a slot for admitting the central wire portion of a pull chain, the terminal being so constructed that when it is attached to the 20 chain the slot will be closed, thus obviating the necessity of soldering or further steps in the making of the terminal.

Other objects and advantages will appear in the following specification, and the novel 25 features of the invention will be particularly pointed out in the appended claims.

My invention is illustrated in the accompanying drawings, forming part of this application, in which

30 Figure 1 is a side view of the device, showing one embodiment of the invention,

Figure 2 is an enlarged plan view,

Figure 3 is an enlarged side view, a portion being broken away,

35 Figure 4 is a bottom view,

Figure 5 is a view showing an extension cord being applied to the terminal, and

Figure 6 shows the position of the terminal when the cord has been applied.

40 In carrying out my invention, I make use, as stated, of a piece of thin metal, such as brass. This is stamped into the form shown.

In the drawings, I have illustrated a hexagonal shape as being the preferred form, 45 although other shapes might be used without departing from the invention. It will be observed that the device has a body portion 1 which is curved at its top, as shown at 2, and is provided with a central opening 3.

50 The top is corrugated to provide ridges 4 alternating with grooves 5. Extending from the central opening 3 to the edge at one side is a slot 6.

55 From the foregoing description of the various parts of the device, the operation

thereof may be readily understood. The main feature of the invention, as stated before, is to provide a terminal which can be cheaply made but which will have a pleasing appearance and which will not crush under 60 the ordinary force used in manipulating the electric switch, although the device is made of sheet metal which is relatively thin.

The terminal is attached to the chain by slipping the central wire portion 7 of the 65 chain into the slot 6. In order to guide it into the slot, I preferably widen the latter slightly, as shown at 6' in Figure 3. One of the balls 8 of the chain is slipped underneath the opening 3, where it is centered. Owing 70 to the corrugations, the sides of the slot will spring together so that it will be virtually closed as shown in Figure 1, thereby obviating the necessity of any further steps in the manufacture. I have found that where 75 these corrugations are not present, as for instance where the terminal is made of a smooth, hemispherical shell, there will not be this spring action which tends to close the slot and that the slot will remain open. The 80 corrugating of the terminal, therefore, has a double function. It makes possible the use of a very thin piece of metal in the making of a terminal which would otherwise be crushed out of shape and at the same time 85 it provides a spring action, so that when the chain is in position, the slot will be closed. It is necessary that the axis of the corrugations be substantially transverse to the direction of the slot. If, for instance, the corrugations were concentric with the opening 3, then the slot from the central opening to the edge would not close but would remain open. The provision of the corrugations 90 also prevents any possibility of the chain pulling out from the opening by the springing away of the metal.

It will be seen that I have provided a terminal which can be made of very thin metal at one stamping operation. The terminal is 100 designed to take the place of the ball terminals which are difficult to make because they require a number of operations, thus increasing the cost.

Another useful feature connected with my 105 improved terminal is that it may be used in connection with an extension cord by merely looping the cord over the terminal. Thus in Figure 5 I have shown the terminal as being reversed from the position shown in 110

Figure 1; that is to say, the bottom ball of the ball chain is outside instead of inside. It is only necessary to loop the cord 9 over the upper end of the terminal and then pull 5 it down so that the terminal will then assume the position shown in Figure 6 and the edge of the terminal next to the cord will keep it in position during use. Ordinarily, with terminals of other types, the 10 cords have to be tied to prevent disengagement of the cord during use.

I claim:

1. A pull chain terminal, comprising a single piece of relatively thin metal stamped 15 into bell shape and having radially extending ridges and grooves on its closed end, said closed end having a central opening, and a slot from said central opening to the edge of the terminal.

2. A pull chain terminal, comprising a 20 single piece of metal stamped into bell shape and having corrugations extending from a point near the center of the closed end toward the edge of the bell shaped piece, said closed end having a central opening, and a 25 slot extending from said central opening to the edge of the terminal, the longitudinal axis of the slot being at right angles to the axis of the adjacent corrugations.

3. A pull chain terminal comprising a 30 single piece of relatively thin metal stamped into bell shape and having radially extending ridges and grooves on its closed end, said terminal being adapted to be reversed 35 upon the pull chain, said closed end having a central opening and a slot from said central opening to the edge of the terminal.

JOHN J. COOK.
